Patented Sept. 2, 1919.

G. A. Wedin

By his Attorney

W C Carlson

UNITED STATES PATENT OFFICE.

GUSTAF ADOLF WEDIN, OF BROOKLYN, NEW YORK.

HOLDER FOR TOWELS AND THE LIKE.

1,314,625.

Specification of Letters Patent.

Patented Sept. 2, 1919.

Application filed May 7, 1917. Serial No. 166,901.

To all whom it may concern:

Be it known that I, GUSTAF ADOLF WEDIN, a citizen of the United States, and a resident of the borough of Brooklyn, in the county of Kings and State of New York, have invented certain new and useful Improvements in Holders for Towels and the like, of which the following is a specification.

10 This invention relates to means adapted for gripping and holding articles by frictional adherence, and it appertains more particularly to holders for towels and similar wares made of some textile fabric.

15 One of the objects of the invention is to produce an improved holder of the nature set forth wherein the article to be held is quickly inserted, and from which it can be as readily removed, without danger of injury to the same.

20 Another object is to provide a holder of the species mentioned which shall be equally efficient in operation whether the articles held thereby be thin or thick, smooth surfaced, or uneven in textures.

25 A further object is the production of a holder of the character described which shall be of simple construction, convenient to operate, and composed of but few parts, severally amenable to low cost of manufacture.

30 Other objects and advantages will become apparent as the specification proceeds.

With the aforesaid objects in view, the invention consists of the improvements, 35 novel construction, arrangements and combinations of parts hereinafter described, defined in the subjoined claims, and illustrated in their preferred embodiments by the annexed drawings, wherein like elements 40 are designated by the same reference characters throughout.

In the said drawings:—

Figure I is a top plan view, partly in section, showing a towel holder made according to the present invention;

Fig. II is a front elevation of the same, the internal parts on the left-hand side being diagrammatically represented, that is, in outline merely;

Fig. III is a vertical transverse section, taken centrally across Fig. II, looking toward the right; and

Fig. IV is a side elevation, looking from the left of Fig. II.

55 Pursuant to one embodiment of the invention, and as shown in the accompanying

drawing, the holder includes a frame having opposed members, as 11, 12, set and maintained at a suitable distance apart. As seen in Figs. II to IV, these members may be disposed on straight parallel lines and thus will constitute the top and bottom members of the frame, respectively.

Within the said frame are placed one or more pairs of gripping elements 15, 16 both of a flexible and inherently elastic nature, which are conveniently attached to the opposed members 11, 12 and likewise arranged in opposed relation. The said elements may consist, for example of tufts of brush bristles, which may be of hair or fiber; or again the tufts may be composed of strips of semi-rigid leather or pliant wicker. By preference the tufts are placed in parallel rows, longitudinally of the frame, as indicated in Figs. I and III, and the several rows of opposed tufts are spaced endwise from one another, so that a short interval will keep them normally separated, as shown at 17, Figs. II and IV.

Fig. III illustrates how a towel, as 19, or a wash-cloth or the like, may be inserted in the holder, and kept safely suspended therefrom in a cleanly condition. When thus inserting an article of the kind referred to, 85 any part of the same may be taken hold of by one or more fingers, and simply pushed in between the free ends of the tufts 15 and 16, the cloth covering the fingers on all sides, so that they do not come in contact with the 90 bristles. The latter yieldingly bend backward during the operation, as represented in said Fig. III. If then the hand be withdrawn, the towel or other article will be caught between and held by the tufts, each 95 individual bristle therein acting as a pawl to engage the woven surface of the article and preventing it from falling off by its own weight or from being too easily disengaged. The thickness of the material of which the 100 article is composed will keep it in place by preventing the tufts from springing back of themselves alone or unaided. But, by applying sufficient force to overcome the gripping power or frictional adherence of the 105 tufts, the article can be quickly released and drawn out, in which case the bristles momentarily swing outward, that is, in a direction opposite to that illustrated in Fig. III, and subsequently become normalized by again 110 springing to their original position.

As represented in Figs. I and II, the par-

allel rows of tufts are preferably arranged so as to form a plurality of groups within the holder and provide empty spaces, as 21, 22 and 23 between the tufts and the ends of the frame, and intermediately of the groups themselves. Several advantages are thereby gained. For instance, this arrangement of the parts enables the hand of the operator to straddle either or any of the groups of tufts in case the article to be introduced therebetween is made of material too thick to permit also the insertion of the fingers wrapped in the material. In such a contingency, the article can be inserted in the holder by pushing it in from the opposite sides of any one group of tufts, as will be easily understood. The grouping of the tufts further effects a saving in the quantities of bristles employed. Moreover, it will be seen that in a holder like that shown in the annexed drawing, for instance, a couple of towels, wash-cloths or similar articles, can be accommodated and maintained at the proper distance apart one from the other, in such a manner that the air will freely circulate around and dry them, or keep them in a dry state.

It will be observed by reference to Figs. I, III and IV, that the rows of bristles are located somewhat nearer to the front of the frame than to the back thereof. The front rows of the different groups may be set fairly close to the face of the frame, being situated inside just far enough to guard against the breaking of the pockets for the bristles or the tearing away of the material from which the frame is made. But it is desirable to set the bristles farther inward at the back of the frame, in order to provide a clearance in the rear of the tufts of ample depth to receive the end of the towel or cloth inserted in the holder.

The previously mentioned parallel members 11 and 12 are preferably held in spaced relation one to the other by means of transverse pieces 26, 27 which may be shouldered as shown, and glued, screwed, or otherwise fastened to the said members.

Eye-plates 29 are provided at the upper edge of the member 11 to suspend the holder from nails, screws, hooks, or other suitable retainers attached to a wall or primary support of any desired description. When thus suspended the holder will be flatwise against the wall or support, with the front side only open for the insertion of towels or other articles. If preferred, however, the holder can be attached endwise to the wall or support so that access may be had thereto on either side or both sides, as needed, for which purpose either of the transverse members 26, 27 may be extended above and below the frame, as at 34, 35, respectively, and perforated to afford holes 36, 37 through which the said retainers may be passed. The

construction last referred to is illustrated in Figs. II and IV.

Although this improved device has been described with reference to a holder for towels and the like, it can obviously serve other useful purposes as well. Thus, it affords a convenient means for securing table cloths to out-of-doors tables or counters. It may also be used for holding children's bed-covers securely in the required position. To these ends the transverse pieces 26, 27 of the holder's frame are provided with intermediate perforations as 31, 32, adapted to receive screws, or equivalent fasteners, by means of which the device can be rigidly connected to the underside of a table-top, bed or crib. Notwithstanding further that the frame of the device has been shown in the drawing as made up of separate pieces, (11, 12, 26, 27) no limitation is intended in that respect, since these parts could as well be formed integral with one another.

While a certain preferred embodiment of this device has been shown and described, it will be understood that changes in the form, arrangements, sizes, proportions and details thereof may be made without departing from the scope of the invention as defined by the appended claims.

Having described my invention what I desire to secure by Letters Patent and claim is:—

1. A holder of the class described comprising a skeleton frame, and groups of grippers therein spaced one from the other and from the ends of said frame, said grippers consisting of tufts of flexible and elastic material inverted relatively to one another, the grippers in each group being set nearer to one than to the opposite side of the frame, the arrangement being such that clearance is obtained on all sides of the groups of grippers.

2. A holder of the class described comprising a skeleton frame, and gripping elements of flexible and elastic material respectively projecting from the opposite sides of the frame toward the center thereof, the intermediate sides of the frame being spaced away from said elements at both ends of the frame.

3. A holder of the class described comprising oppositely disposed longitudinal members, grippers therebetween consisting of tufts of flexible and elastic material inverted relatively to one another, an element arranged transversely of said members, and means for attaching said element to a primary support in such a manner as to maintain said grippers extending out in a plane at right angles to the support, whereby access can be had to the grippers from either side.

4. A holder of the class described, comprising oppositely disposed longitudinal

members, grippers therebetween consisting of tufts of flexible and elastic material inverted relatively to one another, transversely arranged elements joining said members, 5 one of said elements having portions extending endwise beyond the latter, said portions and the elements being provided with openings for fastening means at right angles to each other, thereby enabling the members 10 to be fastened to a primary support either

perpendicularly thereto or in parallelism therewith.

Signed at the borough of Manhattan in the county of New York and State of New York this 4th day of May A. D. 1917.

GUSTAF ADOLF WEDIN.
